UNITED STATES PATENT OFFICE.

FRANK C. GRUGAN, OF THE UNITED STATES ARMY, ASSIGNOR TO THE CHIEF SIGNAL OFFICER OF THE UNITED STATES ARMY.

HELIOTROPE.

SPECIFICATION forming part of Letters Patent No. 239,095, dated March 22, 1881.

Application filed January 24, 1881. (No model.)

To all whom it may concern:

Be it known that I, F. C. GRUGAN, first lieutenant of Second Artillery, United States Army, have invented certain new and useful 5 Improvements in Heliotropes; and I do hereby declare that the following is a full, clear, and exact description of the invention, which will enable others skilled in the art to which it app- 10 pertains to make and use the same, reference be- ing had to the accompanying drawings, which form a part of this specification.

My invention relates to an improvement in signaling-heliotropes; and it consists in the peculiar combination and construction of parts 15 whereby a strong, simple, light, and efficient signaling-instrument is produced, as will be more fully described hereinafter.

In the accompanying drawings, Figure 1 is a side elevation of the standard A and its at- 20 tachments, partly in section. Fig. 2 is a top-plan view of the same. Fig. 3 is a front elevation of one of the mirrors. Figs. 4, 5, and 25 6 are enlarged views of the sight. Fig. 7 shows my invention as operated. Fig. 8 is a view of the screen and its operating mechanism. Fig. 9 is a top-plan view of the same. Fig. 10 is a cross-section of the same. Figs. 11 and 12 are detail views.

A represents an ordinary tripod surmounted 30 by a metallic cap, a. Pivoted in a stud, b, pro- jecting from the lower side of the cap a, and depending therefrom, is the lever c, the upper end of which is formed into a cam, and serves to operate a bolt, d, which plays in the upper 35 end of the stud b. The cap a is provided with a transverse L-shaped slot, e, which extends to the center of the cap, made to receive the flanged button or stud which projects from the lower side of the supporting-arm. Secured in 40 the outer end of the slot e is a flat metallic spring, f, which curves up to the center of the cap a and presses against the lower side of the flanges g, which extend over into the slot.

B represents a supporting-arm, which is 45 strengthened by means of the brace h, traversing its center from end to end, and is provided at each end with suitable studs, i i, and tangent- screws k k. About three-quarters of an inch from each end of the supporting-arm is a hole, l,

made to receive the sighting-rod. Projecting 50 from the lower side of the arm B, at the center, is a flanged button, m, which fits into the groove made in the upper side of the cap a. By means of this button the supporting-arm can be piv- 55 oted upon the tripod A and secured in any de- sired position by means of the cam, bolt, and spring described in the preceding paragraph, as shown in Fig. 1.

C represents a mirror, of which there are two, supported in the frame n and provided with 60 the tangent-screw o, by means of which the mirror can be secured at any desired angle. The center of the frame is provided with an opening, p, by means of which it can be secured upon either of the studs i, thereby pivoting the 65 mirror to the supporting-arm, as shown. By means of the tangent-screws k k the mirror may be revolved to any desired angle to the arm. The mirrors are provided with small circular central openings, w, used in sighting the 70 instrument.

Secured to the opposite end of the supporting-arm from that which carries the mirror is the sighting-rod D, which extends through an annular spring-clamp, of which there are two, 75 secured near both ends of the arm. The upper end of the sighting-rod is flattened so as to form a disk, r, and to this flattened portion is se- 80 cured a flat metallic spring, s, the disk of which has a circular hole, t, as shown in Fig. 4.

Secured between the spring s and the rod- 85 disk r is a piece of white paper or card-board, v, which is tightly held in position by means of the spring, that portion of the paper uncov- 90 ered by the circular opening t being thus ren- dered visible from the front side of the sight- ing-rod. Upon this piece of paper is thrown the dark spot caused by the opening w in the mirror. As the efficiency of the instrument de- 95 pends in a great measure upon the accuracy of the sight, this being determined by keeping the dark spot projected from the center of the mirror upon the center of the disk, it is necessary that the disk should present a perfectly white surface, so as to cause the greatest possible con- trast between it and the dark spot thrown upon it. This I accomplish by making the disk of white paper, and as soon as it has become tar-

nished it can be taken out and replaced by a clean piece at any time by means of the clamping-spring *s*, as described.

I am aware that the use of paper as a disk upon which to project the dark spot is old in signaling-instruments of this kind, and this I disclaim; but the manner here provided of removing and replacing it when it becomes soiled is new and original with me. In packing the instrument the sighting-rod is secured against the longitudinal brace *n* by means of the spring *x*, fastened thereto, the other end of the rod resting against one of the square raised ends of the arm, as shown in Figs. 1 and 2.

E is a second tripod, the legs of which are secured to the casting *y*, consisting of the radial arms *z* and the central core, *z'*. Depending from the lower side of this casting is a cam-lever and bolt precisely similar to those secured to the cap *a* of the standard *A*. At the outer end of the arms *z* are projections *z*², which extend above the top surface of the casting *y*, and are beveled on their inner sides at about an angle of forty-five degrees, as shown in Fig. 8. These beveled projections serve to secure the base of the operating-screen.

F represents the operating-screen. 1 is a circular base, beveled to the same angle as the projections *z*², and made to fit upon the top of the casting *y*, being secured thereto by means of its beveled edge and the projections *z*². In order to insert it into the circle indicated by the radial arms *z*, portions of its edge are removed in three places, as shown in Fig. 10. When the base has been secured within the angular flange of the projections *z*² it is rigidly held in position by means of the cam and bolt previously described. The upper end of the bolt is bored out, so as to form a socket for the projecting head of the screw 2, which secures the operating-rod 3 to the base. Projecting from the upper side of the base 1 is the hollow shaft 4, in which is secured the operating-rod 3. One-fourth of the upper edge of the shaft 4 is cut away, and from the rod 3, extending into the cut-away portion of the shaft, is the projection 5. By means of this arrangement the rod 3 is prevented from moving through more than a quarter of a circle. Above the upper edge of the shaft 4 the rod is enlarged to the diameter of the shaft. This enlargement extends to within about an inch of the top of the rod, and in it is cut a screw-thread. Upon this screw-thread is fitted a wooden handle or key, 6, which is confined at the top by the pin 7. Encircling the shaft 4 and the lower end of the screw 8 is a coiled spring, 9, which extends from the top of the base 1 to the lower side of the key 6. The operating-screw *F* is secured by one of its edges in a slot cut in a hollow rod, 10, and clamped in place by means of a nut, 11. The lower end of the rod 10 fits on the top of the rod 3,

and is caused to partake of its motion by means of the transverse slots 12, which override the ends of the pin 7, extending through the rod 3.

The operation of my invention is as follows: The tripod *A* is first set up, and to it is secured the supporting-arm *B*. Upon one of the studs *i* is secured a mirror, *C*, and the sighting-rod *D* is fixed to the opposite end of the arm. The operator then looks through the central hole of the mirror and brings the disk of the sighting-rod directly in line with the distant station to which the message is to be sent. Having secured the arm from further rotation by means of the clamping devices provided for that purpose, the mirror is brought to such an angle and inclination that the reflection from it is thrown directly to the distant station, this being determined by bringing the dark spot caused by the hole in its center directly in the center of the white disk of the sighting-rod. The second tripod, *E*, is then placed directly in line with the distant station, and the screen adjusted in such a position as to intercept the reflection from the mirror, thus preventing its being seen at the distant station, as shown. If, now, the key 6 be depressed, the screen will move through a quarter of a circle to a position parallel to the line of reflection, and the flash will be distinctly observed at the distant station. This position of the screen is represented in the drawings by dotted lines. When the pressure is removed from the key the spring 9 causes the screen to move back to its initial position, and the reflection of the mirror is cutoff from the distant station. When the sun is behind the operator, a second mirror is substituted for the sighting-rod, in the manner common to all sun-signaling instruments in use, and the screen is operated as before.

Having described my invention, I claim and desire to secure by Letters Patent—

1. The cap *a*, having a slot, *e*, and spring *f*, in combination with the cam-lever *c* and bolt *d*, by means of which the supporting-arm of the instrument may be pivoted and secured in position, substantially as described.

2. In a heliotrope, the supporting-arm *B*, pivoted in its center, and provided with studs and tangent-screws and apertures *l* at either end, whereby a mirror may be carried at either end, (or a mirror and sighting-rod, as may be required,) in combination with the mirror *C* and sighting-rod *D*, substantially as shown.

3. The sighting-rod *D*, flattened at one extremity and provided with the spring *s*, by means of which a paper or other suitable disk may be held securely in position or removed and replaced at will, in combination with the arm *B* and mirror *C*, substantially as and for the purpose set forth.

4. The screen *F*, secured to the hollow rod 10, the lower end of the rod being made to fit over the upper end of the operating-rod, and engaging with it by means of the slot 12 and projection 7, or its equivalent, whereby the

screen may be caused to partake of the motion of the said operating-rod, or readily removed therefrom, substantially as described.

5. The combination of the base 1, hollow shaft 4, operating-rod 3, engaging with said shaft by means of the projection 5, and screw 8, passing through the operating-key, and being partially rotated thereby, whereby the screen may be caused to move back and forth, substantially as shown.

6. The base 1, hollow shaft 4, operating-rod 3, engaging with said shaft by means of the

projection 5, and screw 8, passing through the operating-key, and being partially rotated thereby, in combination with the spring 9, substantially as described. 15

In testimony that I claim the foregoing as my own I have hereto affixed my signature in presence of two witnesses.

FRANK CARTER GRUGAN,

1st Lieut. 2d Artillery.
